AUTOMATIC FEED MECHANISM FOR PUNCH-
ING AND STAMPING PRESSES

John Haller, Northville, Mich.

Application April 26, 1944, Serial No. 532,894

20 Claims. (Cl. 164—117)

The present invention relates to improvements in strip feeding mechanisms for punching and stamping presses.

The primary object of the invention is to provide an automatic feeding mechanism for punching and stamping presses which will intermittently feed the material between the die members of the punch press in timed relation to the stroke thereof so as to increase the production output and thereby increase the efficiency of the press.

Another object of the invention is to provide an intermittent strip feed for punching and stamping machines which is entirely automatic in operation and eliminates the necessity of the operator placing the hands in close relation to the die members of the punching and stamping press to thereby avoid dangerous accidents.

Another object of the invention is to provide a fluid pressure mechanism operably connected to the ram head of a punching and stamping press for controlling the movement of a feed plunger having intermittent gripping devices for engaging the work or strip and advancing the same between the die members of said press so as to eliminate the use of various gears, rotatably driven rollers and other mechanical devices liable to become out of order and broken or damaged.

Another object of the invention is to provide an automatic feed mechanism for punching and stamping presses in which the stroke of the feed may be regulated in accordance with the size of the blanking removed from the strip without altering the speed of the stamping and punching press or altering the parts of the feed mechanism materially.

Another object of the invention is to provide an automatic feed mechanism for punching and stamping presses so as to enable the material being stamped to be fed in strip form and advanced in timed relation with the reciprocating motion of the punch press ram so that the ram will move upwardly away from the work a short interval of time prior to the advancement of the work or strip.

Another object of the invention is to provide an automatic feed mechanism for punching and stamping presses as set forth in the preceding object in which the vertical movement of the ram and operation of the intermittent feed mechanism may be so regulated as to permit the feeding operation at various heights of vertical ram movement to allow the feeding of strips varying in thickness.

Other objects and advantages will become ap-

parent during the course of the following description of the accompanying drawings wherein:

Figure 1 is a top plan view of the intermittent feed mechanism embodying the invention showing a portion thereof broken away to illustrate a by-pass valve arrangement for the fluid pressure system;

Figure 2 is a longitudinal cross sectional view taken on the zig-zag line 2—2 of Figure 1 looking in the direction of the arrows and illustrating various details of construction and the general arrangement of the parts thereof;

Figure 3 is a vertical cross sectional view taken on line 3—3 of Figure 1 looking in the direction of the arrows illustrating the arrangement of the feed plunger as well as one of the intermittent grip devices;

Figure 4 is a vertical cross sectional view taken on line 4—4 of Figure 1 looking in the direction of the arrows to illustrate the movable cross head upon which is supported the other intermittent grip feed device;

Figure 5 is a vertical cross sectional view taken on line 5—5 of Figure 2 looking in the direction of the arrows and illustrating the general structure of the force plunger and cylinder and the various passageways for communicating said plunger to opposite sides of the feed plunger;

Figure 6 is a vertical cross sectional view of one of the intermittent grip devices and illustrating the eccentric position thereof as well as the spring pressed plunger for urging the grip device toward the strip being fed;

Figure 7 is a horizontal fragmentary cross sectional view taken on line 7—7 of Figure 6 and looking in the direction of the arrows to further illustrate various features and structural details of the intermittent grip device; and

Figure 8 is a front elevational view of a punching and stamping press illustrating the manner in which the feed mechanism is applied thereto.

In the drawings, wherein for the purpose of illustrating the invention like reference characters will be employed to designate like parts throughout, the reference character 5 will be employed to indicate a bolster platform of a punching and stamping press (Figure 8) of the crank type having an upper frame portion 6 and a ram 7. The ram 7 is slidably mounted in suitable ways in the frame portion 6 and is provided with a reciprocating rod 8 adjustably connected to the ram 7 to facilitate the adjustment thereof. The lower end of the ram 7 is provided with a male die member 9 which is held within the

ram by means of suitable bolts or the like (not shown). Bolted to the bolster platform 5 is a female die member 10 having its base 11 bolted in place by means of bolts 12 in the usual manner. A guide bracket 13 is affixed to the female die member 10 and said bracket has one of its arms formed with a tubular portion 14 to provide a guide passageway therethrough.

The above description is typical of a conventional punching and stamping press in which a blanking is stamped from a strip S presented between the male and female die members 9 and 10 so that the blanking will be projected through openings in the female die member.

The invention comprises a feed mechanism for advancing the strips S to the male and female die members 9 and 10 in timed relation with the reciprocation of the ram head 7. As shown in Figure 1, the invention embodies a casting generally indicated by the reference character 15 and said casting is provided with a base 16 adapted to be fastened to the bolster platform 5 by means of machine screws or the like as at 17. The upper portion of the casting 16 is cylindrical as at 18 to provide a cylinder structure having a bore 19 for accommodating a fluid pressure piston generally represented by the reference character 20. The lower portion of the casting 5 is provided with branch extensions 21 and 22 to provide an opening 23 directly beneath the cylinder 18 so as to provide a passage through the casting 16 for a strip S as it is intermittently fed to the male and female die members 9 and 10. The piston 20 is secured to the reduced end 24 of a piston rod 25 and comprises cup-shaped packing elements 26 spaced by means of a washer or the like as at 27 and as indicated in Figure 5, the oppositely disposed cup-shaped packing members 26 are clamped between clamping discs 28 on opposite sides thereof so as to be retained in position by means of a nut or the like as at 29. The opposite piston washer 28 engages the shoulder of the reduced portion 24 of the piston rod 25. The upper end of the cylinder is adapted to be closed by a plug cover member 30 having a central bore 31 for permitting passage of the piston rod 25, and said cover plug is held in place by machine screws or the like 35. The bore 31 is enlarged as at 32 for receiving packing material which is adapted to be compressed into contractual engagement with the piston rod 25 by means of a packing gland 33 held in place by machine screws or the like as at 34.

The upper end of the piston rod 25 is screw-threaded for the major portion of its length as at 36 and is adapted to be slidably connected to a bracket arm 38 secured to the ram head 7 by means of machine screws or the like as at 39. Stop nuts 40 and 41 are threaded on the threaded portion 36 of the piston rod 25 so that there will be delayed action between the movement of the ram head 7 and the movement of the piston 20 in both directions of reciprocating motion of the ram head.

Formed on the base 16 of the casing 15 and extending inwardly of the horizontal opening 23 is a pair of oppositely disposed enlarged bosses 42 and 43 having horizontal bores 44 and 45 respectively. Tubular shafts 46 and 47 are fitted in the respective bores 44 and 45 and are held therein by being sweated in place or otherwise secured. The tubular shafts 46 and 47 are provided with axial bores 48 and 49 having radially extending bores 50 and 51 at one end thereof in

registry with ducts or passageways 52 and 53 in the casting 15 adjacent the enlarged bosses 42 and 43. The duct 52 is in communication with a vertically extending bore 54 extending through the wing extension 21 and said vertical bore 54 is adapted to communicate with the cylinder bore 19 on one side of the piston 20 by means of a horizontal duct or passageway 55. Similarly, the duct or passageway 53 is in communication with a vertical bore 56 which extends through the wing extension 22 to a point adjacent the upper end of the cylinder bore 19 so that communication between the vertical bore 56 may be had with the cylinder bore 19 by means of a horizontal duct or passageway 57. As shown in Figure 5, the various bore are provided with closure plugs 60 to facilitate intermittent cleaning thereof upon removal of said threaded plug 60. It will thus be seen that reciprocation motion imparted to the piston 20 in either of its two directions of movement will cause a fluid pressure in one or the other of the axial bores 48 of the tubular shafts 46 and 47. Screw-threaded plugs 61 and 62 are received in correspondingly threaded openings in the ends of the tubular shafts 46 and 47 respectively so as to close said ends against the escape of liquid in the pressure system.

Supported on the free ends of the tubular shafts 46 and 47 is a casting generally indicated by the reference character 65 and said casting is shaped to provide a cylinder 66 having a bore 67. Diametrically opposed tubular extensions 68 and 69 are formed on the cylinder 66 and are provided with bores 70 and 71 for the reception of the reduced ends 72 and 73 of the respective tubular shafts 46 and 47. It is to be noted that the tubular extensions 68 and 69 extend the full length of the cylinder 66 as do the reduced portions 70 and 71 of the tubular shafts 46 and 47, and that said shafts project slightly beyond the rear wall of the cylinder and are threaded for receiving anchoring nuts 74.

The front wall of the cylinder 66 is closed by means of an end wall 75 having a bore 76 for slidably receiving a piston rod 77 and said bore 76 is enlarged as at 78 for receiving a packing element 79 which is held in place by means of a packing gland 80. Machine screws or the like as at 81 are provided for securing the packing gland 80 in place and prevent the escape of fluid around the piston rod 77. One end of the piston rod 77 is reduced as at 82 for receiving a piston structure generally indicated by the reference character 83 and said piston embodies a disc 84 received on the reduced end of the shaft 82 having oppositely disposed cup-shaped piston packings 85 and 86. Clamping washers 87 and 88 are disposed on opposite sides of the cup-shaped piston packings 85 and 86 and are adapted to be moved toward the piston disc 84 into clamping engagement therewith by means of a tightening nut 90 threaded on said reduced end 82 of the piston rod 77. The other end of the piston rod 77 is reduced as at 91 for receiving a cross head generally designated by the reference character 92 and said cross head is provided with oppositely disposed wing portions 93 and 94 having parallel bores 95 and 96 for receiving the respective tubular guide rods 46 and 47. The cross head 92 is slidably mounted on the tubular guide rods 46 and 47 and connection between the piston rod 77 and said guide rods is effected by means of said reduced end 91 being received in an opening 97 held in place by a nut or the

like as at 98 threaded thereon. A pair of up-standing lugs 100 are formed on the cross head 92 in spaced apart relation having aligned bores therein as at 101 for receiving a spindle 102 (Figure 4).

A roller 105 is eccentrically mounted on the spindle 102 and the ends of said roller 105 are provided with short pin extensions 106 threaded therein as at 107 so as to project into a vertical slot 108 (Figures 6 and 7) in the upstanding lugs 100. The upper portion of the slot 108 in each of the lug extensions 100 is reduced to provide a bore 109 in which is slidably received a plunger 110 for engaging the pin extension 106 and urging the same downwardly. A coil spring 111 is mounted in the bore 109 and a screw threaded plug 112 is mounted in an enlarged threaded portion 113 of said bore 109 so as to compress the spring 111 and tension the plunger 110. The structure above described provides a friction gripping element for engaging the work strip S during unidirectional movement of the cross head 92 so as to feed said strip when the cross head 92 is moved in the direction of the casting 15.

Secured to the cross head 92 as by means of machine screws or the like 115 is a contact plate 116 slightly spaced from the friction gripping roller 105 so that the eccentric roller 105 will engage the strip S during said unidirectional movement of the cross head and urge the strip into frictional engagement with the contact plate 116. A set screw 117 may extend through a threaded opening in the roller 105 to secure said roller upon the spindle 102 and prevent lateral movement thereof and displacement from the bores 101 in the upstanding lug 100.

Similarly, a friction-gripping roller 120 is mounted on the casting 65 and eccentrically positioned upon a shaft 121 having its ends supported by upstanding lugs or the like as at 122 formed integral with the casting 55. A set screw 123 is provided for securing the eccentric friction gripping roller 120 in position on the shaft 121 and said roller 120 is provided with oppositely extending pin projections 124 similar to the pin projections 106 (Figures 6 and 7) which extend into openings or slots 125 in the integral upstanding lugs 122. A spring pressed plunger engages the oppositely extending pin projections 124 in identically the same manner as described in connection with the eccentric friction gripping roller 105 carried by the cross head 92 so that a description of one will suffice for both. A contact plate 127 is disposed beneath the eccentric friction-gripping roller 120 and is secured to the cylinder 66 by means of screws or the like (not shown). Set screws 128 are threaded in suitable bores in the upstanding lugs 122.

It is to be noted that one end of each of the shafts 102 and 121 projects beyond its respective upstanding lug 100 and 122 and is provided with handles 130 and 131 to facilitate partial rotation of said eccentric friction-gripping rollers 105 and 120 during its positioning or initial feeding of the strip therethrough so as to register the end of the strip with the tubular guide 14 adjacent the female die member 10 and establish the desired distance between said rollers.

Communication between the axial bores 48 and 49 of the tubular guide rods 46 and 47 respectively with opposite ends of the cylinder 66 is had through radial bores 133 and 134 which are in registry with ports 135 and 136 respectively inter-communicating each end of the cylinder bore 67. A valve housing is secured to one end of the cyl-

inder 66 and is generally indicated by the reference character 136 and said valve housing comprises a central partition 137 forming valve chambers 138 and 139 on opposite sides thereof. Relatively long machine screws 140 are passed through opening 141 in the valve housing 136 so that the inner threaded ends thereof may be received in corresponding threaded bores 142 in the end wall of the cylinder 66. The joint between the valve casting 136 and the end of the cylinder 66 may be sealed by means of a packing element 144 interposed therebetween and when the machine screws 140 are tightened in place, said casting 136 will be drawn tightly against the end of the cylinder 66 in such a manner as to prevent the escape of fluid therefrom. It is to be noted that the valve casting 136 is provided with bores 145 and 146 through which extend the ends of the respective tubular guide shafts 46 and 47 so that the axial bores thereof as at 48 and 49 will communicate with the valve chambers 138 and 139 respectively. The partition wall 137 is provided with openings or passageways 147 and 148 having valve seats 149 and 150 respectively for poppet type valves 151 and 152. The poppet valves have their stems 153 and 154 slidably guided in valve guides 155 and 156 extending into the respective valve chambers 138 and 139. The valve guides 155 and 156 are threaded as at 157 and 158 for being received in correspondingly threaded openings 159 and 160 in the side walls of the casting 136 so that said stems may be projected through the threaded openings 159 and 160 and tightened in place by applying a wrench to the polygonal ends 161 and 162 thereof. Suitable coil springs 153a and 154a encircle the valve stems 153 and 154 to normally hold said valves closed on their respective seats. Said coil springs engage the ends of the valve guides at one of their ends and have their other end in abutting engagement with the valve heads. It will thus be seen that a closed fluid pressure system is provided in which fluid pressure developed on opposite sides of the piston 20 will be transmitted to opposite sides of the piston 83 and thereby cause reciprocation of the cross head 92 and advance the strip S toward the male and female die members 9 and 10 of the punch press.

The cross head 92 has secured to the wing extensions 93 and 94 thereof a pair of screw threaded rods 163 which are fixed to the wing extensions by being threaded in suitable openings therein as at 164. The opposite ends of the screw threaded rods 163 extend on opposite sides of the casting 65 and are slidably mounted in a bracket generally indicated as at 166 supported on the cylinder 66 as well as the diametrically opposed tubular extensions 68 and 69 at each side thereof. The bracket 166 is provided with a pair of oppositely disposed slots 167 for receiving the diametrically flattened side 168 of the screw-threaded shaft 163. In this manner, the threads of the screw threaded shaft 163 are guided in the slots 167 without mutilating the threads of the shaft and said screw shafts are further guided in slots 165 within oppositely extending lugs 169 formed integral with the diametrically opposed tubular extensions 68 and 69 and at one end thereof. Similar slots are formed in the lugs 169 which likewise engage the flattened opposed surfaces 168 of the screw-threaded shaft 163 to slidably guide the same during the reciprocating movement of the cross head 92. Limit stop nuts 170 and 171 are threaded on the screw threaded shafts 163 so as to limit the reciprocating movement of the

cross head 92 in accordance with the size of the blanking desired. The stop nuts 170 and 171 are adapted to alternately engage the lug projections 169 and bracket 166 between the limits of the cross head travel 92.

Formed in the bracket 166 is a cutaway portion 172 over which is positioned a strap 173 held in place by machine screws 174 or the like to thereby provide a space of sufficient width and length to facilitate the passage of the strip S being fed to the die members. Supported on the strap 173 and depending therefrom is a pair of guide rollers 175 mounted on bolts 176. A longitudinal slot 177 is formed in the strap 173 for receiving the upper reduced and threaded ends of the bolts 176 so as to clamp the shoulders of said bolts against the underside of the strap 173 when the nuts on said threaded ends as at 178 are tightened in place. The adjustable rollers 175 may be moved toward and away from each other along the slots 177 so that the flanges thereof as at 179 will extend above and below the strip S and thereby guide said strip by edge contact therewith and simultaneously hold the strip against vibration in a vertical direction during the feeding or advancement thereof to the male and female die members 9 and 10.

Various screw plugs 180 may be threaded in correspondingly threaded openings in alignment with the radially extending bores 135 and 136 communicating the cylinder bore 167 with the tubular guide rods 46 and 47 so as to facilitate cleaning of said bores and the removal of sediment therefrom. It is understood that the tubular guide rods 46 and 47 have their reduced ends received in the bores 70 and 71 of the diametrically opposed tubular extensions 68 and 69 respectively by means of the shoulder 181 thereof abutting the ends of said diametrically opposed tubular extensions 58 and 59. The other ends of the tubular guide rods 46 and 47 are similarly anchored in the casting 15 with the shoulder of the other reduced end of said guide rod arranged in abutting relationship with the casting 15 so that the machine screws 61 and 62 will clampingly urge said rods in position.

For consideration of the operation of the feeding mechanism for stamping and punching machines, attention is directed to Figure 8 and it will be assumed that the casting 15 has had its base 16 bolted to the bolster platform 5 of the stamping and punching machine and that the piston rod 25 is affixed for sliding movement within the opening in the end of the bracket 38 carried by the punching and stamping machine ram head 7 so that movement of the ram head will cause reciprocating movement of the piston 20 after the ram head has travelled downwardly a predetermined distance and likewise upwardly a predetermined distance so as to alternately engage the stop nuts 40 and 41. After the intermittent feeding mechanism has thus been attached to the stamping and punching machine, the strip of metal or other material is fed endwise between the rollers 175 with the flanges thereof as at 179 extending above and below the edges of said strip. The end of the strip is then presented to the eccentrically mounted friction roller 120 and by manipulating the hand piece, said roller may be rotated slightly against the action of the coil spring 111 so as to permit the strip to be passed thereunder and above the contact plate 126. Upon reeling the hand piece 131, the roller is urged into engagement with the strip S to hold the same against retrograde move-

ment but yet permit forward feeding thereof. The end of the strip is next fed under the eccentrically mounted friction gripping roller 105 by similarly manipulating the handpiece 130 to partially rotate the eccentrically mounted roller against the action of the coil spring 111 with the cross head 92 arranged in a position and adjusted by manipulation of the limit stop nuts 170 and 171 to more accurately regulate the stroke of the cross head 92 in proportion to the size of the blanking or stamping desired.

When the strip has thus been manually fed to the intermittent feeding mechanism, the punch press or stamping machine may be operated to cause the reciprocation of the ram head 7 which will likewise effect the reciprocation of the piston 20 and the reciprocation of the piston 83 in the cylinder 86 by fluid transmission. Upon the downward movement of the ram head 7, the bracket arm 38 will engage the stop nut 40 and force the piston downwardly so as to move the piston 83 to the right (Figure 2) or toward the valve casting 136. During this movement of the piston 83, and the cross head 92 the strip is held beneath the male and female die members 9 and 10 respectively by the eccentrically mounted friction gripping roller 120. When the piston 83 has reached the limit of its movement, depending on the adjustment of the limit stops 170 and 171, the die members will have blanked the strip in the usual manner. Upon the upward movement of the ram head 7 the stop nut 40 on the piston rod 25 will be engaged after a predetermined travel of said ram head a distance sufficient to permit the separation of said die members and free the strip S. Upon continued upward movement of the ram head, the piston rod 25 is moved upwardly to compress the fluid on the opposite side of the piston 20 and thereby cause the movement of the piston 83 in such a direction as to advance the cross head 92 from its retracted position. During the advance movement of the cross head 92 the eccentrically mounted friction gripping roller 105 engages the strip S and frictionally holds the same in engagement with the contact strip 116 so as to simultaneously move said strip a sufficient distance to present another portion of the strip S and advance the same between the die members 9 and 10.

It is noted that the cylinder 18 is of a diameter slightly larger than the cylinder 66 and that the pistons 20 and 83 are likewise of different diameters. This structure provides an increase in power and prevents the stamping and pressing machine from being unduly loaded to the extent of disturbing the operation thereof and permits said stamping machine to be operated continuously so as to increase production. In order to overcome the differential piston diameters and cylinder dimensions, the spring seated valves 151 and 152 are arranged so as to allow excess fluid to travel from one compartment to the other and facilitate equal displacement without interruption of the feed mechanism or the stroke of the cross head 92. For instance, on the down stroke of the piston 20 a greater volume of fluid will be displaced than can be accommodated in the cylinder 66 and in order to overcome this differential fluid volume the valve 152 will be unseated from its seat 150 so as to allow the excess liquid to flow to the chamber 139 on the other side of the partition or dividing wall 131 of the valve casting 136. Upon reverse movement of the piston 20 or during its upward travel, the same condition will exist and there will be a

greater volume of liquid being fed to the cylinder 66 than can be accommodated by the bore thereof or by reason of the transfer of the fluid to the opposite sides of the partition 137 of said valve casting 136. In order to overcome this difference in the fluid volume the valve 152 may be urged away from its seat upon movement of the piston 83 to the limit of its travel so as to allow the escape or transference of excessive liquid from the chamber 139 to the chamber 138 on the opposite sides of the partition 137 of the valve casting 136.

It is to be understood that the closed fluid system involving the cylinders 18 and 66 is to be filled with a suitable fluid such as oil or the like so as to cause the movement of the piston 83 by fluid transmission in response to the movement of the piston 20. During each movement of the ram head 7 a slight delayed action will occur depending upon the spacing of the stop nuts 40 and 41. The various cycles of the above operation are repeated continuously to provide an intermittent feeding of the strip S between the male and female die members 9 and 10 and thereby eliminate the stopping and starting of the stamping and punching press as is the case when the press is hand fed.

It is also to be understood that the intermittent automatic feeding mechanism herewith shown and described may be applied to various stamping and punching machines without materially altering the structure of the stamping machine per se and that the form and shape of the intermittent automatic feeding mechanism may be changed and the parts thereof may be variously arranged without departing from the spirit of the invention or the scope of the subjoined claims.

What I claim is:

1. In combination with a stamping and punching machine having a bolster platform and a ram head, a feed mechanism supported on said platform comprising a base, fluid pressure means mounted on said base operatively connected to said ram, guide means on said base, a reciprocating member mounted on said guide means, motor means carried by said guide means responsive to said fluid pressure means and operatively connected to said reciprocating member, and intermittent work engaging means on said reciprocating member and said base to engage and feed material to said ram head upon reciprocation of said ram head and reciprocation of said reciprocating member.

2. In combination with a stamping and punching machine having a bolster platform and a ram head, a feed mechanism supported on said platform comprising a base, pressure means mounted on said base adapted to be operated by said ram head guide means on said base, a reciprocating member mounted on said guide means, motor means supported by said guide means drivingly connected to said reciprocating member, means for connecting said pressure means and motor means in fluid transmission relationship, and intermittent work engaging means on said reciprocating member and said base to engage and feed material beneath said ram head upon reciprocation of said ram head and reciprocating member.

3. In combination with a stamping and punching machine having a bolster platform and a ram head, a feed mechanism supported on said platform comprising a base, guide means on said base, a reciprocating member mounted on said

guide means, intermittent work engaging means on said reciprocating member and said base to engage and feed material to said ram head upon reciprocation of said reciprocating member, and fluid pressure means controlled by the movement of the ram head for reciprocation of said reciprocating member.

4. In combination with a stamping and punching machine having a bolster platform and a ram head, a feed mechanism supported on said platform comprising a base, guide means on said base, a reciprocating member mounted on said guide means, intermittent work engaging means on said reciprocating member and said base to engage and feed material to said ram head upon reciprocation of said reciprocating member, and fluid transmission means operatively connecting the ram head with the reciprocating member to cause the feeding of material between said ram head and bolster platform in timed relation to the movement of said ram head.

5. In combination with a stamping and punching machine having a bolster platform and a ram head, a feed mechanism supported on said platform comprising a base, guide means on said base, a fluid pump operatively connected to said ram head, a reciprocating member mounted on said guide means, intermittent work engaging means on said reciprocating member and said base to engage and feed material to said ram head upon reciprocation of said reciprocating member, motor means drivingly connected to said reciprocating member, and means connecting the pump and motor in fluid transmission relationship for reciprocating the reciprocating member in timed relation.

6. In combination with a stamping and punching machine having a bolster platform and a ram head, a feed mechanism for advancing material between the ram head and bolster platform in timed relation to the movement of said ram head comprising a base affixed to said platform, a pump connected to said ram head, guide means secured to said base, material supporting means spaced from and connected to said base, a cross head movable between the supporting means and said base, a motor drivingly connected to said cross-head, means carried by the material supporting means and cross head for frictionally engaging and feeding material to the platform upon movement of said cross head in one direction with respect to said platform, and fluid transmission means operatively connecting said pump to the motor, whereby reciprocation of said ram head will cause reciprocation of said cross head and advance material between the ram head and bolster platform.

7. In combination with a stamping and punching machine having a bolster platform and a ram head, a feed mechanism for advancing material between the ram head and bolster platform in timed relation to the movement of said ram head comprising a base affixed to said platform, guide means secured to said base, material supporting means spaced from and connected to said base, a cross head movable between the supporting means and said base, means carried by the material supporting means and cross head for frictionally engaging and feeding material to the platform upon movement of said cross head in one direction with respect to said platform, fluid pressure means operatively connecting said ram head to the cross head to advance material therebeneath upon vertical upward movement of said ram head, and means for limiting the stroke

of said cross head to permit the advancement of material predetermined distances.

8. In combination with a stamping and punching machine having a bolster platform and a ram head, a feed mechanism for advancing material between the ram head and bolster platform in timed relation to the movement of said ram head comprising a base affixed to said platform, guide means secured to said base, material supporting means spaced from and connected to said base, a cross head movable between the supporting means and said base, means carried by the material supporting means and cross head for frictionally engaging and feeding material to the platform upon movement of said cross head in one direction with respect to said platform, and fluid pressure means operatively connecting said ram head to the cross head to advance material therebeneath upon vertical upward movement of said ram head.

9. In combination with a stamping and punching machine having a bolster platform and a ram head, a feed mechanism for advancing material between the ram head and bolster platform in timed relation to the movement of said ram head comprising a base affixed to said platform, guide means secured to said base, material supporting means spaced from and connected to said base, a cross head movable between the supporting means and said base, means carried by the material supporting means and cross head for frictionally engaging and feeding material to the platform upon movement of said cross head in one direction with respect to said platform, and fluid pressure means operatively connecting said ram head to the cross head to advance material therebeneath upon vertical upward movement of said ram head, said means for frictionally engaging the material including an eccentrically mounted friction roller yieldingly urged about its axis into gripping relation with said material upon partial rotation thereof.

10. In combination with a stamping and punching machine having a bolster platform and ram head, a feed mechanism for advancing material between the ram head and bolster platform in timed relation to the movement of said ram head comprising a base affixed to said platform, guide means secured to said base, material supporting means spaced from and connected to said base, a cross head movable between the supporting means and said base, means carried by the material supporting means and cross head for frictionally engaging and feeding material to the platform upon movement of said cross head in one direction with respect to said platform, fluid pressure means operatively connecting said ram head to the crosshead to advance material therebeneath upon vertical upward movement of said ram head, and guide means carried by said material supporting means for engaging the edges of said material to hold the same in true alignment with said feed mechanism.

11. An intermittent feed mechanism for punching and stamping machines having a bolster platform and a ram head, comprising a base, adapted to be affixed to said platform in close proximity to the ram head, a guide member extending laterally from said base, a support mounted on the outer end of said guide member, a cross head reciprocably mounted on the guide member, friction gripping devices on the supporting member and cross head for engaging and feeding material to the ram head, and fluid pres-

sure means operatively connecting said ram head to the crosshead to cause said cross head to move in timed relation to the movement of said ram head.

5 12. An intermittent feed mechanism for punching and stamping machines having a bolster platform and a ram head, comprising a base adapted to be affixed to said platform in close proximity to the ram head, a guide member extending laterally from said base, a support mounted on the outer end of said guide member, a cross head reciprocably mounted on the guide member, friction gripping devices on the supporting member and cross head for engaging and feeding material to the ram head, and fluid pressure means operatively connecting said ram head to the cross head to cause said cross head to move in timed relation to the movement of said ram head, said guide member comprising spaced parallel rods for slidably supporting said cross

20 head.

13. An intermittent feed mechanism for punching and stamping machines having a bolster platform and a ram head, comprising a base adapted to be affixed to said platform in close proximity to the ram head, a guide member extending laterally from said base, a support mounted on the outer end of said guide member, a cross head reciprocably mounted on the guide member, friction gripping devices on the supporting member and cross head for engaging and feeding material to the ram head, fluid pressure means operatively connecting said ram head to the cross head to cause said cross head to move in timed relation to the movement of said ram head, said guide member comprising spaced parallel rods for slidably supporting said cross

25 head.

14. An intermittent feed mechanism for punching and stamping machines having a bolster platform and a ram head, comprising a base adapted to be affixed to said platform in close proximity to the ram head, a guide member extending laterally from said base, a support mounted on the outer end of said guide member, a cross head reciprocably mounted on the guide member, friction gripping devices on the supporting member and cross head for engaging and feeding material to the ram head, fluid pressure means operatively connecting said ram head to the cross head to cause said cross head to move in timed relation to the movement of said ram head, and means for limiting the movement of the cross head to regulate the stroke thereof and feed predetermined lengths of material to said ram head.

40

15. An intermittent feed mechanism for stamping and punching machines having a bolster platform and a reciprocating ram head, comprising a base affixed to said platform, a fluid pressure cylinder carried by said base, a pair of guide bars connecting said base and extending laterally therefrom, a cylinder carried by said guide bars having fluid connection with said first-mentioned cylinder, a crosshead slidably mounted on said guide bars to move between the limits of said base and second-mentioned cylinder, friction gripping members carried by said cross head and second-mentioned cylinder to alternately engage and feed material to said ram head, means connecting one of said pistons to the ram head and means connecting the other piston to said cross head whereby movement of said ram head will re-

ciprocate said cross head and feed material between the ram head and bolster platform.

16. An intermittent feed mechanism for stamping and punching machines having a bolster platform and a reciprocating ram head, comprising a base affixed to said platform, a fluid pressure cylinder carried by said base, a pair of guide bars connecting said base and extending laterally therefrom, a cylinder carried by said guide bars having fluid connection with said first-mentioned cylinder, a cross head slidably mounted on said guide bars to move between the limits of said base and second-mentioned cylinder, friction gripping members carried by said cross head and second-mentioned cylinder to alternately engage and feed material to said ram head, means connecting one of said pistons to the ram head, and means connecting the other piston to said crosshead whereby movement of said ram head will reciprocate said cross head and feed material between the ram head and bolster platform, said friction gripping members consisting of eccentrically mounted rolls yieldingly urged into engagement with material being fed to the ram head.

17. An intermittent feed mechanism for stamping and punching machines having a bolster platform and a reciprocating ram head, comprising a base affixed to said platform, a fluid pressure cylinder carried by said base, a pair of guide bars connecting said base and extending laterally therefrom, a cylinder carried by said guide bars having fluid connection with said first-mentioned cylinder, a cross head slidably mounted on said guide bars to move between the limits of said base and second-mentioned cylinder, friction gripping members carried by said cross head and second-mentioned cylinder to alternately engage and feed material to said ram head, means connecting one of said pistons to the ram head, said means connecting the other piston to said cross head whereby movement of said ram head will reciprocate said cross head and feed material between the ram head and bolster platform, said base being provided with a passageway in alignment with said second-mentioned cylinder to permit material in strip form to be fed to the ram head upon reciprocation of said cross head.

18. An intermittent feed mechanism for stamping and punching machines having a bolster platform and a reciprocating ram head, comprising a base affixed to said platform, a fluid pressure cylinder carried by said base, a pair of guide bars connecting said base and extending laterally therefrom, a cylinder carried by said guide bars having fluid connection with said first-mentioned cylinder, a cross head slidably mounted on said guide bars to move between the limits of said base and second-mentioned cylinder, friction gripping members carried by said cross head and second-mentioned cylinder to alternately engage and feed material to said ram head, means connecting one

of said pistons to the ram head, means connecting the other piston to said cross head whereby movement of said ram head will reciprocate said cross head and feed material between the ram head and bolster platform, and stop members supported by the base for limiting the stroke of said cross head to permit the advancement of predetermined lengths of material to the ram head.

19. An intermittent feed mechanism for stamping and punching machines having a bolster platform and a reciprocating ram head, comprising a base affixed to said platform, a fluid pressure cylinder carried by said base, a pair of guide bars connecting said base and extending laterally therefrom, a cylinder carried by said guide bars having fluid connection with said first-mentioned cylinder, a cross head slidably mounted on said guide bars to move between the limits of said base and second-mentioned cylinder, friction gripping members carried by said cross head and second-mentioned cylinder to alternately engage and feed material to said ram head, means connecting one of said pistons to the ram head and means connecting the other piston to said cross head whereby movement of said ram head will reciprocate said cross head and feed material between the ram head and bolster platform, said friction gripping members consisting of eccentrically mounted rolls yieldingly urged into engagement with material being fed to the ram head.

20. An intermittent feed mechanism for stamping and punching machines having a bolster platform and a reciprocating ram head, comprising a base affixed to said platform, a fluid pressure cylinder carried by said base, a pair of guide bars connecting said base and extending laterally therefrom, a cylinder carried by said guide bars having fluid connection with said first-mentioned cylinder, a cross head slidably mounted on said guide bars to move between the limits of said base and second-mentioned cylinder, friction gripping members carried by said cross head and second-mentioned cylinder to alternately engage and feed material to said ram head, means connecting one of said pistons to the ram head, means connecting the other piston to said cross head whereby movement of said ram head will reciprocate said cross head and feed material between the ram head and bolster platform, means for adjusting the stroke of said cross head, and means carried by said second-mentioned cylinder for guiding and engaging the side edges of material being fed to the ram head.

JOHN HALLER.
